UNITED STATES PATENT OFFICE.

HOWARD W. UNDERWOOD, OF MOYLAN, PENNSYLVANIA, ASSIGNOR TO FIELD, BARKER & UNDERWOOD, OF PHILADELPHIA, PENNSYLVANIA, A CORPORATION OF NEW JERSEY.

ROAD MACHINE.

Application filed October 10, 1921. Serial No. 506,753.

This invention relates to road-making machinery, and more particularly to machinery for concrete roads.

In laying concrete roads, it is necessary that the concrete be allowed to set under moisture, which latter is sometimes applied by the so-called "ponding" process, in which the necessary dams are built and the whole surface of the concrete flooded over with water; and sometimes, where the nature of the operation will not permit of the puddling process, by covering the concrete over with loose dirt or sand and wetting down this covering. In this latter process, it has been customary in the past to apply this dirt covering by shoveling the dirt from the sides of the road onto the concrete, which method has been found, for certain reasons hereinafter set forth, unsatisfactory, and the principal object of the present invention is to provide mechanical means for spreading this covering over the concrete and thereby to avoid the aforesaid disadvantages.

25 In the attached drawings:

Figure 1, is a plan view of a machine made in accordance with my invention;

Fig. 2, is a front elevation of the machine, and

Fig. 3, is an end elevation.

With reference to the drawings, the machine comprises an open-frame truck consisting of three lateral cross beams 1, 2 and 3, united by a plurality of cross beams 4, the said beams 1, 2 and 3, being in the present instance in the form of eye sections and the cross beams 4 being angle irons arranged in pairs, one pair at each side of the machine and underlying the said beams 1, 2 and 3.

As best shown in Figs. 2 and 3, the respective pairs of cross beams 4 carry at both their forward and rear ends bearings 5 for wheels 6, said bearings depending from the beams and the wheels 6 being of the flange type, as clearly shown.

Mounted in bearings 7, 7, at one end of the beams 1 and 2, is a shaft 8 which carries a pulley or roller 9, there being also mounted upon these cross beams with their axes parallel to the axis of the said roller 9, a plurality of rollers 10, 11, 12 and 13, upon which and the roller 9 operates an endless belt conveyer 14. As clearly shown,

the rollers 10 are mounted in bearings supported upon uprights 15 carried upon the cross beams 1 and 2, and with the roller 12 whose bearings are mounted upon a superstructure 16 upon the said cross beams, have their tops substantially in horizontal alignment with the top of the roller 9. The roller 11 on the other hand is mounted between the beams 1 and 2 with its under side in substantial alignment with the under side of the roller 9, the roller 13, also mounted between the beams 1 and 2, providing a support for the belt intermediate the roller 11 and the roller 9. The superstructure 16 in the present instance is so secured to the cross beams 1 and 2 as to be adjustable longitudinally of the beams, thereby providing means for taking up slack in the conveyer belt. The bearings 7, 7, of the roller 9 also are adjustable longitudinally of the beams 1 and 2, providing an additional take up for the conveyer belt and also a take up and adjustment for the sprocket chain 18.

The shaft 8 of the roller 9 extends at one side and carries a sprocket 17 which is connected by means of a sprocket chain 18 with a sprocket wheel 19 mounted on a shaft 20. The shaft 20 is carried in bearings 21, 21, one of which is mounted upon the beam 2, and the other upon a beam 22 extending between the beams 2 and 3. A bevel gear 23 is fixed to one end of the shaft 20 and meshes with a bevel 24 upon a shaft 25, which latter shaft is carried in bearings 26, 26, mounted upon uprights 27 and 28 respectively secured to beams 29 and 30 extending between the cross beams 2 and 3. The shaft 25 is operatively connected by means of a gear wheel 31, pinion 32 and gears 33 and 34 with an engine or motor 35, which latter is supported in suitable manner upon a beam 36 extending between the cross beams 2 and 3 and upon the beam 30.

As clearly shown in the drawings, the pinion 32 and the gear wheel 33 are carried by a shaft 37 mounted in a sleeve 38 on the engine body, the gear wheel 34 being secured to the main shaft 39 of the motor, which shaft in the present instance also carries fly wheels 40, 40.

Mounted in bearings 41, 41, upon two of the cross beams 4 and upon the beams 22 and 29, is a shaft 42, said shaft having at each end a pinion 43 which meshes with

2
gear wheels 44, 44, one of which is secured in suitable manner to each of the front wheels 6 of the truck, interconnection between the shaft 42 and the shaft 25 being provided for by means of a gear wheel 45 carried by the shaft 42 and a pinion 46 upon the shaft 25, a further connection between these two shafts being accomplished by means of sprocket wheels 47 and 48 carried respectively by the shafts 25 and 42 and by means of an associated sprocket chain 49. The gear wheel 45 and the sprocket 47 are each loosely mounted upon their respective shafts, and clutches 50 and 51 are provided whereby these elements may be made fast to the shafts, there being provided hand levers 52 and 53 for manipulating the respective clutches. It will be apparent that depending on whether the drive takes place through gears 45 and 46 or the sprockets 47 and 48, this shaft will be driven in one direction or the other, the gears being employed for moving the car in a forward direction and the sprockets for reverse.

25 Mounted upon the superstructure 16 at one end of the cross beams 1 and 2, is a hopper 54, said hopper immediately overlying one end of the endless belt conveyor 14, and having its bottom and the lower portion of its forward end 54^a open, whereby material thrown into the hopper is carried forwardly by the belt 14, which moves in the direction of the arrow, Fig. 1, and out through the open end 54^a.

30 35 Supported at the rear of the truck upon uprights 55, secured to the cross beam 1 at spaced intervals, are a series of distributing elements in the form of triangular wedge-like plows 56, said plows, as best shown in Fig. 1, being distributed across the back of the truck and being in number and width sufficient to substantially overlie the entire width of the roadbed. The said uprights 55 are preferably adjustably secured to the beam 1 to permit vertical adjustment of the distributing elements to vary the space between these and the underlying roadbed.

40 45 50 Carried upon the cross beams 1 and 2 and comprising cross bars 57 which bridge the space between the said cross beams and overlie the belt 14, is a series of superstructures which constitute supports for a series of deflector blades 58, 59, 60 and 61, these blades being secured to and depending from the bridge pieces 57, and being disposed one directly in front of each of the points of the respective plows 56. As best shown in Fig. 1, these deflector blades 58 are disposed at an angle to the direction of movement of the belt with one end lying substantially over the rear edge of the belt and with their lower edges in close proximity to the belt's upper surface. Of these deflector blades, the blade nearest the hopper, design-

nated by the numeral 58, is less in width than any of the others, each of the blades 59, 60 and 61, increasing in width by predetermined increments equal substantially to the width of the blade 58. In this manner as the dirt or other material is carried from the hopper 54 outwardly upon the belt, each of the blades deflects from the belt approximately the same amount of the conveyed material, which is accordingly deflected laterally from the belt and falls to the roadbed directly in front of the noses of the respective plows.

55 60 65 In order to prevent the dirt from collecting upon the parts of the truck and upon the lower side of the belt, deflectors 62 are employed, as best shown in Fig. 3, which guide the dirt outwardly away from the lower portion of the belt. A suitable scraper 63 is also provided so positioned and supported by the cross beams 1 and 2 as to scrape the inside of the belt free from any material that may collect there.

70 75 80 85 As best shown in Fig. 2, the truck is adapted to travel upon rails or beams 64, 64, which constitute the side forms between which the concrete is confined, these side beams in the present instance being formed of metal of suitable cross section to present a smooth and vertical surface to the concrete and a flat horizontal surface as the track for the wheels.

90 95 100 105 It will be noted that in the present instance the blade 61 is not quite wide enough to completely lie across the entire width of the belt, thereby permitting a small amount of dirt to be carried to the end where it falls to the roadbed; and furthermore, the plow 56 at this side of the machine is left at some distance from the end of the belt and from the side of the underlying roadbed. The dirt or sand which passes over the roller 9 accordingly collects in a pile or ridge near the side rail and gives a surplus for covering the edge of the concrete when 110 the form or rail is removed. This pile may be simply pushed over the edge of the concrete and saves long carry by shovel from the opposite side of the road where the dirt is located. There is, of course, dirt available 115 at the said opposite side of the road to cover the exposed edge of the concrete without extra labor.

120 125 130 The ends of the beams 1 and 2 which support the hopper 54 project outwardly beyond the beams 4, 4, at that side of the truck and in such manner that the said hopper overlies the ground at the side of the roadbed, thereby providing easy access to the hopper to the men who supply the dirt or sand which forms the road covering, said dirt or sand as previously stated being deposited at this side of the road.

It will also be noted that the beam 3 is extended beyond the cross beams 4 on the 130

hopper side of the truck, and the cross beams 4, 4, at this end of the truck are made detachable from the cross beams 1, 2 and 3, to permit their being moved outwardly 5 when it is desired to use the machine on roads of greater width. For this purpose also, the shaft 42 is formed of separate parts connected by means of a suitable coupling 65, thereby to permit the necessary extension 10 of the shaft 42 by the insertion of short sections.

The operation of the machine is as follows: The machine is stationed at one end of the stretch of concrete over which it is 15 desired to spread the layer of dirt or sand and the engine set in motion to advance the machine down the road, the wheels, as previously described, traveling upon the bounding bars for the concrete which constitute 20 tracks. As the machine travels slowly over the concrete, the hopper is fed with the dirt or sand by operators who maintain their position opposite the hopper, the dirt being carried by the endless belt conveyer 25 from the hopper and being deflected by the deflector blades in such a manner as to fall in front of the respective spreading elements. These latter are so shaped and positioned relative to each other that this 30 deposited dirt or sand is spread in a substantially even layer over the surface of the concrete.

The machine has been found to effect a substantial economy in this particular 35 spreading operation in the process of concrete road-building, this saving being found in the fact of the great accessibility to the men handling the dirt of the hopper, which eliminates the necessity for their throwing 40 the dirt out over the concrete. Heretofore, also, in order to obtain a proper distribution 45 of the dirt over the concrete, it has been necessary for the men on occasion to step out on the surface of the concrete, and accordingly by using this machine, the covering 50 can be placed sooner on fresh concrete because of the fact that no walking on the surface is necessary. This early covering and wetting is of considerable advantage 55 in the curing process.

It will be apparent that numerous modifications over the form of the machine herein described may be possible with no departure 60 from the essential features of the invention.

55 I claim:

1. In a machine of the type specified, the combination with a traveling frame, of a belt conveyer carried by and movable laterally of the frame, means intermediate the 65 ends of the conveyer for deflecting material therefrom in, operative engagement with and overlying said conveyer to the ground surface over which the said frame travels, and means for distributing the material over 70 said surface.

2. In a machine of the type specified, the combination with a traveling frame, of means carried by the frame for depositing material therefrom at a plurality of transversely positioned points upon the ground 75 surface over which the frame travels, an element carried by said frame rearwardly of the point at which the said deposit is made and adapted to operate upon the deposited material to spread it in a substantially even layer over the said surface, and means for adjusting the spreading element to vary the depth of the material spread upon the surface.

3. In a machine of the type specified, the combination with a traveling frame, of a belt conveyer carried by and movable laterally of the frame, and deflector blades disposed at intervals above and in operative engagement with the conveyer and adapted 85 to deflect material from the conveyer to the ground surface over which the frame travels.

4. In a machine of the type specified, the combination with a traveling frame, of a 90 conveyer carried by and movable laterally of said frame, and a series of deflectors positioned above the conveyer and at intervals along its length and adapted to deflect material from the conveyer, the deflector blades 95 having one vertical edge substantially overlying one edge of the conveyer and increasing uniformly in width in the direction of movement of the conveyer.

5. In a machine of the type specified, the combination with a traveling frame, of a 100 conveyer carried by and movable laterally of the frame, a plurality of spaced deflectors adapted to deflect material from the conveyer, and a spreader disposed rearwardly 105 of each of said deflectors for distributing the material over the ground surface over which the frame travels.

6. In a machine of the type specified, the combination with a traveling frame, of a 110 conveyer carried by and movable laterally of the frame and projecting at one side beyond the side of the frame, and a hopper carried by the frame and disposed over the projecting end of the conveyer.

7. In a machine of the type specified, a supporting frame comprising a plurality of lateral beams united by cross beams, wheels mounted on said cross beams and supporting the frame, means for adjusting one set of 115 said cross beams longitudinally of the said lateral beams to vary the distance between the opposed sets of wheels, a conveyer carried by and movable laterally of the frame, and deflector blades disposed at intervals 120 above the conveyer and adapted to deflect material from the conveyer to the ground surface over which the frame travels.
